ALARM SYSTEM

Alfred H. Faulkner, Chicago, Ill., assignor to General Telephone Laboratories, Incorporated, a corporation of Delaware

Application February 17, 1956, Serial No. 566,281

13 Claims. (Cl. 340—213)

The present invention relates to alarm systems and particularly to electronically controlled circuits for such systems.

An object of the invention is to provide an improved alarm system having a central station and a plurality of control stations connected thereto in a normally closed circuit arrangement wherein an alarm is rendered at the central station in response to an abnormal condition at any one of the control stations and wherein another alarm is rendered at the central station in response to an interruption of any one of the connections between the central station and the control stations.

Another object of the invention is to provide in an alarm system of the closed circuit type improved operating circuits having low power requirements.

A further object of the invention is to provide in an alarm system of the closed circuit type improved operating circuits utilizing transistors and diodes to perform the control operations therein.

A further object of the invention is to provide in an alarm system including a plurality of line circuits respectively associated with the control stations thereof an improved transistorized line circuit operated in a normal state in response to a normal condition at the corresponding control station and operated in a first alarm state in response to an abnormal condition at the corresponding control station and operated in a second alarm state in response to an interruption in the connection between the line circuit and the corresponding control station.

An additional object of the invention is to provide in an alarm system line circuit control means for controlling the line circuits thereof through any of their operating states in order to restore to the normal operating state any line circuit operated to an alarm state and in order to test the alarm operation of any of the line circuits.

Further features of the invention pertain to the particular arrangement of circuit elements in the alarm system, whereby the above outlined objects and additional operating features thereof are attained.

The invention both as to its organization and method of operation, taken together with further objects and advantages thereof, will be best understood by reference to the following specification taken in conjunction with the accompanying drawing in which Figures 1 and 2, taken together, illustrate in schematic form a high temperature alarm system and the apparatus included therein embodying the principles of the present invention.

Section 1.—The high temperature alarm system

More particularly, Figures 1 and 2 illustrate a high temperature alarm system having a central station 10 serving a plurality of temperature control stations, including the temperature control stations 20 and 30. A plurality of two conductor control lines, including the control lines 246 and 248, respectively connect the temperature control stations 20, etc., to the central station 10. In the temperature control stations 20, etc., the conductors

2

of the corresponding control lines 246, etc., are connected together through temperature-sensitive impedance devices, including the temperature-sensitive impedance devices 250 and 255, so that the impedance of the path completed thereover is varied in accordance with changes in the temperature at the corresponding temperature control station. In the central station 10, the control lines 246, etc., are terminated respectively in line circuits, including the line circuits 220 and 220A, which are selectively operated in accordance with the impedance established in the path extending through the conductors of the corresponding control line. In the central station 10, the line circuits 220, etc., are commonly connected to power equipment which supplies power thereto and to alarm equipment which may be operated in response to signals received from any one of said line circuits.

Referring specifically to Fig. 1, the terminal equipment located in the central station 10 includes a power supply 100 adapted to convert alternating current power to direct current power for operating the fire alarm system, a grounded line detector unit 110, a trouble alarm controller 130 responsive to trouble signals returned from the line circuits 220, etc., a temperature alarm controller 140 responsive to temperature alarm signals returned from the line circuits 220, etc., a voltage regulator 150 for distributing a constant voltage-variable current to the line circuits, a temperature alarm 187, a trouble alarm 190, a test switch 180 for testing the operation of the line circuits 220, etc., and a flasher unit 160 for supplying a flashing signal to an attendant at the central station 10 when the test switch 180 is operated into a test position.

Figure 2 illustrates two of the line circuits 220 and 220A, which are identical in structure and which are connected respectively through line circuit control switches, including the control switches 240 and 240A, to the corresponding control lines 246, etc. In the temperature control stations 20, etc., the temperature sensitive impedance devices 250, etc., respectively complete a connection between the conductors of the corresponding control lines and under normal temperature conditions thereat exhibit a high impedance to current flow therethrough and under high temperature conditions thereat exhibit a low impedance to current flow therethrough.

Section 2.—The equipment of the alarm system

Considering now the equipment included in the high temperature alarm system, the system is designed to operate on 120 volt D. C. current supplied to power terminals 203 and 204 on the terminal block 202 from a 120 volt D. C. power source or, alternatively, from a 120 volt A. C. power source. From a D. C. source, power is applied over the input line 91, including the negative and positive input conductors 91A and 91B, respectively, which are connected directly to negative and positive power conductors 193 and 194 terminated at the power terminals 203 and 204, respectively. From an A. C. source, power is applied over the input line 92 including the negative and positive input conductors 92A and 92B, respectively, directly to the primary winding of a step-up transformer T109 located in the power supply 100.

The power supply 100, which is connected at its output to the power conductors 193 and 194, is of a conventional arrangement and includes in addition to the step-up transformer T109, a bridge rectifier provided with diodes D101, D102, D103 and D104, a filter reactor L105 bridged by a capacitor C106 in order to minimize the peak to peak value of the ripple in the output voltage of the rectifier, and a pair of parallel coupled filter capacitors C107 and C108. A pilot lamp LP111 of the neon discharge type is connected in series with a resistor 112 across the power conductors 193 and 194.

and is illuminated when power is being applied to the power conductors 193 and 194 thereby indicating the operative state of the alarm system. In addition, a grounded line detector unit 110 including resistors 113, 114, and 115 and line conductor ground lamps LP116 and LP117, of the neon discharge type, are connected across the conductors 193 and 194 in order to render an indication when any line conductor in the system is grounded as will be described in detail hereinafter.

The trouble alarm controller 130 is connected via conductor 195 to a terminal 205 on the terminal block 202 and includes the transistor TR131 arranged to amplify trouble alarm signals received over conductor 195 and to operate a trouble relay R136 for completing an operating circuit through the trouble alarm 190 which may be of the buzzer type. The temperature alarm controller 140 is connected via conductor 196 to a terminal 206 on the terminal block 202 and includes the transistor TR141 arranged to amplify temperature alarm signals received over conductor 196 and to operate a temperature relay R146 for completing an operating circuit through temperature alarm 187 which may be of the ring type.

The voltage regulator 150 supplies a constant-voltage current via conductor 197 to the terminal 207 on the terminal block 202, and the regulator comprises a load resistor 159 for establishing a fixed voltage on the terminal 207 and transistors TR151, TR152, TR153 and TR154 connected therein for varying the current flow in conductor 197 in accordance with current demands made at the terminal 207.

The test switch 180 is a three position switch, and has associated therewith the temperature alarm 187, the trouble alarm 190, a temperature test alarm lamp LP189 of the neon discharge type and a trouble alarm test lamp LP192 of the neon discharge type. In its normal position the test switch 180 connects the temperature alarm 187 and the trouble alarm 190 to the respective operating circuits therefor; in a temperature alarm test position the test switch 180 disconnects the temperature alarm 187 from the corresponding one of the above mentioned operating circuits and connects the temperature alarm test lamp LP189 to that circuit and also completes a circuit for operating the flasher unit 160; and in a trouble alarm test position the test switch 180 disconnects the trouble alarm 190 from the other of the above mentioned operating circuits and connects the trouble alarm test lamp LP192 to that circuit and also completes a circuit for operating the flasher unit 160.

The flasher unit 160 illustrated in Figure 1 includes transistors TR161 and TR162 connected in a relaxation oscillator circuit to provide a square wave output voltage, and a test lamp LP171 of the neon discharge type which is operated by the square wave output voltage.

Referring now to Figure 2, the line circuits 220 and 220A shown in detail therein are identical; and the line circuit 220 includes the transistors TR221, TR222 and TR223, a temperature alarm lamp LP227 and a trouble alarm lamp LP230, both of the neon discharge type. The high temperature alarm system operates on a closed circuit basis so that normally a circuit is completed from the positive voltage on the terminal 204 to the negative voltage on the terminal 203 through the line circuit 220, the associated line circuit control switch 240, the control line 246 and the temperature-sensitive impedance device 250 located at the temperature control station 20. The line circuit control switch 240 is accessible to an attendant at the central station 10 and is operable from a normal position into a temperature alarm test position and from the normal position through a line cut-off position and into a trouble alarm test position. In the normal position the line circuit control switch 240 completes the above traced circuit through the temperature-sensitive impedance device 250 in the temperature control station 20 and between the terminals 203 and 204; in the tem-

perature alarm test position the line control circuit 240 completes a connection between the conductors 246A and 246B of the control line 246 so that the temperature-sensitive device is short circuited and an effective low impedance condition therefor is displayed to the line circuit 220; in the line cut-off condition the normal connection at the switch 240 to the conductors 246A and 246B is interrupted; and in the trouble alarm test position, a load resistor 247, of an impedance comparable to the normal temperature impedance of the temperature-sensitive impedance device 250, is connected to the line circuit 220.

Each of the temperature-sensitive impedance devices 250, etc., located in the temperature control stations 20, etc., may be different in a minor respect as will be pointed out hereinafter, but are alike in the respect that at normal temperatures each exhibits a high impedance to current flow therethrough and at temperatures above a critical normal temperature exhibits a low impedance to current flow therethrough. Specifically, the temperature-sensitive impedance device 250 located in the temperature control station 20 includes a mercury column switch 251 connected across the line conductors 246A and 246B of the control line 246 in a normally open circuit arrangement and a load resistor 252 connected across the line conductors 246A and 246B in parallel with the mercury column switch 251 to establish a high impedance connection between the line conductors. At a predetermined high temperature the mercury column switch 251 is closed so that the load resistor 252 is shunted by the mercury column and a low impedance connection is completed between the line conductors. An alternative embodiment is the temperature-sensitive impedance device 255 of temperature control station 30 which comprises two mercury column switches 256 and 257 arranged in spaced apart relationship in the temperature control station and a load resistor 258, all connected in parallel and operating substantially as the temperature sensitive impedance device 250 so that at normal temperatures a high impedance connection is established across line conductors 248A and 248B of the control line 248 and at a predetermined high temperature either or both of the mercury column switches 256 and 257 are closed and a low impedance connection is established across the line conductors 248A and 248B.

The operation of the equipment included in the high temperature alarm system will be better understood from the following considerations of: operation under normal temperature conditions; operation when a high temperature condition exists therein; operation when a fault condition exists therein; and operation when any one of a number of test conditions is imposed thereon.

Section 3.—Operation of the high temperature system under normal temperature conditions

At the central station 10, the potential across the power conductors 193 and 194, applied either directly from the D. C. input conductors 91A and 91B or through the power supply 100 from the A. C. input conductors 92A and 92B, is 120 volts, which causes the pilot lamp LP111, to break down and to sustain a current flow therethrough for illuminating the lamp. The failure of the pilot lamp LP111 to illuminate indicates that power is not being applied to the input conductors or, if the A. C. power source is being utilized, that some fault lies in the power supply 100.

The power conductors 193 and 194, the line circuits 220, etc., the conductors of the control lines 246, etc., and the temperature-sensitive impedance devices 250, etc. are normally not grounded so that the potential with reference ground established at the power conductors 193 and 194 and the corresponding terminals 203 and 204 depends upon the distribution of leakage resistance between elements of the system and ground. The system is designed so that in normal use the leakage resistances

between the conductors of the control lines 246, etc., extending from the line circuits 220, etc., to the temperature control stations 20, etc., and ground are predominant and are balanced with respect to the power conductors 193 and 194 so that in the system voltages with respect to ground at these conductors and at their terminals 203 and 204 are, respectively, -60 volts and +60 volts, the voltages with respect to ground on the conductors of the control lines extending to the control stations 20, etc., such, for example, as conductors 246A and 246B of the control line 246 are, respectively, -40 volts and +40 volts, and zero volts with respect to ground is established in the load resistor of each of the temperature-sensitive impedance devices 250, etc.

In order to provide power for operating the trouble alarm controller 130, the temperature alarm controller 140 and the voltage regulator 150, a voltage divider, including the resistors 120, 121, 122, 123, 124 and 125, is connected between the power conductors 194 and 193 so that at the junction between resistors 120 and 121 the normal voltage is +50 volts, at the junction between resistors 121 and 122 the normal voltage is +47 volts, at the junction between resistors 122 and 123 the normal voltage is +27.5 volts, at the junction between resistors 123 and 124 the normal voltage is -48.5 volts, and at the junction between resistors 124 and 125 the normal voltage is -53.5 volts. The resistor 124 is in fact the terminal to terminal resistance of a potentiometer having a variable center tap 126 on which a voltage in the range from -48.5 volts to -53.5 volts may be established.

In the trouble alarm controller 130 the transistor TR131, which is of the PNP junction type, is normally biased non-conductive by +50 volts applied to the emitter electrode thereof from the junction between resistors 120 and 121 and +50.5 volts established the base electrode by the leakage current flowing in a path via resistors 133 and 132, the base-collector path of transistor TR131, and the winding of relay R136 from +60 volts on the power conductor 194 to +27.5 volts at the junction between resistors 122 and 123. The current flow through the above traced path is less than .05 ma. so that relay R136 is not operated and the voltage established at the junction between resistors 133 and 132 and on the conductor 195 extending therefrom to the terminal 205 at the terminal block 202 is +50 volts. A diode D134 is connected between the base and emitter electrodes of the transistor TR131 in order to limit the reverse bias therebetween and thereby maintain the leakage current through the base-collector path at a minimum. Another diode, D135, is connected from +47 at the junction between resistors 121 and 122 to the junction between resistors 133 and 132 and conductor 195 in order to establish a minimum voltage on the conductor 195 at approximately +47 volts.

The temperature alarm controller 140 is substantially identical to the trouble alarm controller 130 and is connected to the power conductor 194 and to the junctions between resistors 120 and 121 and between resistors 122 and 123 in the same manner as is the trouble alarm controller 130. Thus, the transistor TR141 therein is normally non-conductive, the relay R146 is not operated and the voltage established on the conductor 196 and on the terminal 206 at the terminal block 202 is +50 volts.

Referring now to the voltage regulator 150, the four transistors TR151 to TR154, inclusive, which are of the PNP junction type, are connected in multiple in a modified grounded collector circuit. The collector electrodes of the transistors TR151 to TR154, inclusive, are connected, respectively, through resistors 155 to 158, inclusive, to -60 volts on the power conductor 193 and the emitter electrodes are all connected through the load resistor 159 to +60 volts on the power conductor 194. The base electrodes of the transistors TR151 to TR154, inclusive, are connected to the variable voltage tap 126 of the potentiometer resistance 124 and the voltage there-

on is adjusted so as to render the transistors conductive and to permit a small current in the emitter-collector paths thereof such that normally a current of approximately 5 ma. is drawn through the resistor 159, thereby establishing the voltage on the conductor 197, connected to the junction between resistor 159 and the emitters of the transistors, at -50 volts.

The test switch 180 in its normal position prepares at contacts 183 a circuit extending from +60 volts on the power conductor 194 via contacts 147 the relay R146 and the temperature alarm 187 to -60 volts on the power conductor 193, and prepares at contacts 185 a circuit extending from +60 volts on the power conductor 194 via contacts 137 of the relay R136 and the trouble alarm 190 to -60 volts on the power conductor 193. In the temperature alarm test position the test switch 180 completes at contacts 181 a circuit for operating the flasher unit 160 and opens contacts 183 and closes contacts 182 in order to substitute the series connected resistor 188 and the temperature alarm test lamp LP189 for the temperature alarm 187 in the previously traced circuit. In the trouble alarm test position the test switch 180 completes at contacts 186 a circuit for operating the flasher unit 160 and opens contacts 184 and closes contacts 185 in order to substitute the series connected resistor 191 and the trouble alarm test lamp LP192 for the trouble alarm 190 in the previously traced circuit.

The flasher unit 160, as explained above, is operated only when the test switch 180 is in the temperature alarm test position or the trouble alarm test position. The transistors TR161 and TR162 therein are of the NPN junction type coupled in a relaxation oscillator circuit with the emitter electrodes thereof accessible via contacts 181 or 186 of the test switch 180 to -60 volts on the power conductor 193. The collector electrode of TR161 is connected via resistors 164 and 165, and the collector electrode of TR162 is connected via resistors 167 and 168 to +60 volts on the power conductor 194. The base electrode of TR161 is connected via a charging capacitor C171 to the junction between resistors 167 and 168, and the base electrode of TR162 is connected via a charging capacitor C172 to the junction between resistors 164 and 165. When either of the contacts 181 or 186 is closed -60 volts is applied to the emitters of the transistors TR161 and TR162, whereby, and as will be explained in detail hereinafter, the transistors become alternately conducting so that a substantially square wave voltage signal is developed at the collector electrodes thereof. In order to utilize one of the square wave voltage signals for providing a flashing signal, a voltage divider including resistors 169 and 178 is connected between +60 volts on power conductor 194 and -60 volts on the emitters of TR161 and TR162, and a test position lamp LP171, of the neon discharge type, is connected at one electrode to the junction between resistors 169 and 178 and at the other electrode to the collector of TR162. The manner in which the test position lamp LP171 is operated will be considered in detail hereinafter with the consideration of the operation of the flasher unit 160.

The grounded line detector unit 110 is connected across the power conductors 193 and 194 in order to record a grounded conductor condition in any one of the control lines 246, etc., of the system. Specifically, resistors 113, 114 and 115 are connected in series between the power conductors 193 and 194 so that normally the voltage at the junction between resistors 113 and 114 is -50 volts and the voltage at the junction between resistors 114 and 115 is +50 volts. The positive line conductor ground lamp LP116 is connected at its cathode to the junction between resistors 113 and 114 and at its anode to ground, and the negative line conductor ground lamp LP117 is connected at its anode to the junction between resistors 114 and 115 and at its cathode to ground, so that under normal conditions neither lamp is illuminated. However,

and as explained in detail hereinafter, in response to the grounding of any one of the negative line conductors of the control lines 246, etc., normally at -40 volts, the negative ground detector lamp LP117 is illuminated, and in response to the grounding of any one of the positive line conductors of the control lines 246, etc., normally at +40 volts, the positive ground detector lamp LP116 is illuminated, thereby rendering the attendant at the central station 10 notice of a grounded conductor condition. In order to prevent the lamps LP116 and LP117 from being discharged by instantaneous surges in the voltage on either of the power conductors 193 and 194, a shunting capacitor C118 is connected across the electrodes of the lamp LP116 and a shunting capacitor C119 is connected across the electrodes of the lamp LP117.

In the line circuits, such, for example, as the line circuit 220, the transistors TR221, TR222 and TR223 are all of the NPN junction type. A voltage divider comprising resistors 225, 235, and 233, connected between +60 volts on the terminal 204 of the terminal block 202 and -60 volts on the terminal 203 of the terminal block 202, establishes a voltage at the junction between resistors 225 and 235 and the collector of TR222 of approximately +40 volts and a voltage at the junction between resistors 233 and 235 and the base of TR221 of approximately -10 volts. The emitter of transistor TR222 and the base of the transistor TR223 are fixed at -50 volts by a connection to the common terminal 207 in the terminal block 202. The emitter of transistor TR221 is connected via a resistor 234 to -60 volts at terminal 203 so that TR221 is rendered conductive at the base-emitter path thereof, thereby completing circuit extending from +60 volts on the terminal 204 to -60 volts on the terminal 203. Specifically, the circuit extends from terminal 204 via resistor 224, contacts 244 of the line circuit control switch 240, line conductor 246B, load resistor 252 of the temperature-sensitive impedance device 250, line conductor 246A, contacts 242 of the line circuit control switch 240, resistors 231 and 232, the collector-emitter path of TR221, and resistor 234 to the terminal 203, so that a current of approximately 4 ma. flows therethrough establishing the line conductor 246B at +40 volts, the line conductor 246A at -40 volts, the emitter electrode of TR223 at the junction between resistors 231 and 232 at approximately -48 volts, the base of TR222 and the collector of TR221 at approximately -52 volts and the emitter of TR221 at approximately -53 volts. At this time the emitter of TR222 is at -50 volts so that TR222 is biased non-conductive, by a small current flow of approximately .2 ma. in the collector-base path thereof. The +40 volts at the collector of TR222 is applied via resistor 226 to the anode of the temperature alarm lamp LP227 which lamp has its anode connected to +50 volts on the terminal 206. At the transistor TR223 the collector is connected via resistor 228 to +60 volts on terminal 204, the base is at -50 volts and the emitter is at -48 volts so that a small current of approximately .2 ma. flows in the collector-base path thereof biasing the transistor non-conductive and establishing the collector thereof at approximately +40 volts. The voltage on the collector of TR223 is applied via resistor 229 to the cathode of the trouble alarm lamp LP230 which has its anode connected to +50 volts at the terminal 205. As the potential across the electrodes of the lamps LP227 and LP230 is substantially less than the breakdown voltage, these lamps at this time are non-conducting and not illuminated.

Thus, under normal operating conditions and normal temperature conditions, the test switch 180 and the line circuit control switches 240, etc., are in their normal positions, the pilot lamp LP111 is illuminated, the flasher unit 160 is inoperative, and the line circuits are in an operative state so that in any one thereof, such, for example, as the line circuit 220, the transistor TR221 is

conductive and the transistors TR222 and TR223 are non-conductive.

Further operation of the circuits included in the high temperature alarm system will be understood from the following consideration of a high temperature condition therein.

Section 4.—Operation of the high temperature alarm system when a high temperature condition exists therein

Assuming, now, that the temperature at the temperature control station 20 rises to the predetermined critical high temperature, the mercury column switch 251 of the temperature-sensitive impedance device 250 is closed so that the line conductors 246A and 246B are effectively shortcircuited. Thereupon, the current flow through the line circuit 220 and the line conductors 246A and 246B increased from 4 ma. to about 13.5 ma., causing the potential drop through resistors 231 and 232 to increase so that the base electrode of the transistor TR222 goes from -52 volts to approximately -50 volts. At this time, the emitter electrode of the transistor TR222 is at approximately -50 volts and TR222 is biased conductive so that a large current, initially 9 ma., flows through the base-emitter path thereof, and the potential on the collector electrode swings from +40 volts to approximately -50 volts so that the potential across resistor 226 and the temperature alarm lamp LP227 is increased from approximately 10 volts to approximately 100 volts, and the lamp LP227 breaks down and supports a discharge current of approximately 2 ma. therethrough, whereby the temperature alarm lamp LP227 glows to indicate to an attendant at the central station 10 that a high temperature condition exists in the temperature control station 20.

Normally, the current flow through the resistor 233 is about .35 ma. of which approximately .3 ma. flows through the base of the transistor TR221; the emitter current of the transistor TR221 is approximately 4 ma. so that the current flow into the collector electrode is approximately 3.7 ma. Thereafter, when the transistor TR222 is rendered conductive and the collector voltage is at -50 volts, the voltage on the base of the transistor TR221 changes from -10 volts to -56 volts, thereby causing the collector-emitter current of TR221 to be limited approximately 1 ma.; thereupon the base-emitter current of TR222 is increased to 12.5 ma. At this time, the transistor TR222 is fully conductive and restricts conduction in the transistor TR221 so that TR221 is substantially non-conductive. Should the high temperature condition at the temperature control station 20 subsist thereafter, so that the temperature-sensitive impedance device 250 again exhibits a high impedance characteristic and the current flow in the line conductors is decreased from 13.5 ma. to 4 ma. the transistor TR222 in the line circuit 220 remains conducting because at this time the collector-emitter current of TR221 is limited to approximately 1 ma. so that the transistor TR222 conducts 3 ma. through the base-emitter path thereof. In order to protect the transistor TR222 from false operation due to power surges a shunting capacitor 236 is connected in the line circuit 220.

The anode of the temperature alarm lamp LP227, is maintained at -50 volts by the voltage of the terminal 206 which is applied thereto by conductor 196 from the temperature alarm controller 140. When the lamp LP227 is illuminated and draws a 2 ma. current through the conductor 196 from the temperature alarm controller 140, the transistor TR141 therein is rendered conductive and the relay R146 is operated to close contacts 147 the circuit for operating the temperature alarm 187. Specifically, in the temperature alarm controller 140, 2 ma. current demand of conductor 196 is supplied through resistor 143 and the remaining 1.8 ma. is drawn initially through the diode D145 from +47 volts at the junction between resistors 121 and 122 so that the voltage on the base electrode of the transistor TR141 is established at

approximately -47 volts, whereby the transistor is biased conductive in the emitter-base path thereof and the 1.8 ma. current is supplied from +50 volts at the junction between resistors 120 and 121 through the emitter-base path and resistor 142. In addition current flows in the emitter-collector path of TR141 and the winding of relay R146 to 27.5 volts at the junction between resistors 122 and 123 so that relay R146 is operated and contacts 147 are closed to complete a circuit extending from +60 volts on the power conductor 194, contacts 183 of the test switch 180, the temperature alarm 187 to -60 volts on power conductor 193. At this time the temperature alarm 187 is operated thereby rendering an audible alarm to the attendant at the central station 10 that a high temperature condition exists at one of the temperature control stations served by the high temperature alarm system. The attendant then checks all of the temperature alarm lamps in the system and is given notice by the illuminated condition of the temperature lamp LP227 that the high temperature condition exists in the temperature control station 20.

Again, considering the conduction of the transistor TR222 in the line circuit 220, as previously mentioned, the maximum current flow through the base-emitter path thereof is 12.5 ma. and the current flow via the temperature alarm lamp LP227 and through the collector-emitter path of TR222 is 2 ma. so that the maximum current flow from the emitter electrode of the transistor TR222 is approximately 15 ma. This 15 ma. current flow is applied via the terminal 207 of the terminal block 202, to the conductor 197 extending to the voltage regulator 150. As previously mentioned, the -50 volts on the conductor 197 is normally established by the 5 ma. current flowing from the power conductor 194 through the resistor 159 and the emitter-collector paths of the transistors TR151 to TR154, inclusive, to the power conductor 193. However, when a high temperature condition develops in any one of the control stations 20, etc., the 15 ma. current applied to the conductor 197 tends to reduce the normal 5 ma. current flow through the resistor 159 whereupon the potential drop through the resistor 159 is reduced thereby tending to increase the voltage on the emitter electrodes of the transistors TR151 to TR154, inclusive, and to bias the emitters more positive with respect to their base electrodes. Thereupon the current flow in each of the emitter-collector paths of the transistors is increased by an amount in aggregate substantially equal to the 15 ma. current flow in the conductor 197. Thus, the current flow through the load resistor 159 is substantially unaffected, and the potential on the conductor 197 and the terminal 207 is maintained at -50 volts, whereby the bias voltage furnished from the common terminal 207 to the other of the line circuits 220A, etc., is maintained constant, and these line circuits are maintained in their normal operating state.

In response to the alarm signals of the temperature alarm 187 and the temperature alarm lamp LP227, the attendant at the central station 10 takes proper steps to remedy the high temperature condition existing at the temperature control station 20, and in addition, proceeds to disable the line circuit 220 until the high temperature condition thereat is remedied; whereupon the common equipment at the central station is restored and made available to register any trouble or temperature alarm conditions that may occur thereafter at any of the other of the temperature control stations 30, etc.

Specifically, in order to disable the line circuit 220, the line circuit control switch 240 associated with the line circuit 220 is operated from its normal position through its cut-off to its trouble-test position. As the line circuit control switch 240 is moved through its cut-off position, the circuit extended to the temperature-sensitive impedance device 250 at the temperature control station 20 via the line conductors 246A and 246B is interrupted at contacts 242 and 244. At this time when the previously

traced circuit through transistor TR222 is interrupted so that TR222 is non-conductive, the base potential of TR222 is raised from -56 volts to -10 volts, the collector potential of TR221 and the emitter potential of TR223 is changed to approximately -60 volts so that TR221 and TR223 are biased conductive in the base-emitter paths thereof. Thereupon, transistors TR223 and TR221 are conductive in a path extending from +60 volts at terminal 204 through resistor 228, the collector-emitter path of TR223, resistor 232, the collector-emitter path of TR221 and resistor 234 to -60 volts at terminal 203; the transistor TR221 is non-conductive; and the temperature alarm lamp LP227 is extinguished. The current drawn through the conductor 196 of the temperature alarm controller 140 is reduced from 2 ma. to zero so that the transistor TR141 thereof is rendered non-conductive and the relay R146 is restored. Thereupon, the previously traced circuit for operating the temperature alarm 187 is interrupted at contacts 146. Incidental to the conduction of the transistor TR223, the trouble alarm lamp LP230 is discharged and illuminated in a manner as described in detail hereinafter. However, the lamp LP230 merely flashes, for, as the line circuit control switch 240 passes through its cut-off position into its trouble-test position, the contacts 241 and 243 thereof are closed thereby completing a circuit for rendering the transistor TR223 and the trouble alarm lamp LP230 non-conductive.

Specifically, upon closing, the contacts 241 and 243 connect a load resistor 247 to the line circuit 220 in the place of the circuit extended to the temperature-sensitive impedance device 250 over the line conductors 246A and 246B. The impedance of the load resistor 247 is substantially equal to that of the load resistor 252 in the temperature-sensitive impedance device 250 so that the line circuit 220 is placed in condition for normal operation whereupon a 4 ma. current flows in a path from +60 volts on the terminal 204 through resistor 224, contacts 243, resistor 247, contacts 241, resistors 231 and 232, the collector-emitter path of the transistor TR221, and the resistor 234 to -60 volts on the terminal 203. The potential at the junction between resistors 231 and 232 changes from approximately -50 to -48 volts so that the transistor TR223 is biased non-conductive in the base-emitter path thereof and conduction through the collector-emitter path thereof ceases so that collector voltage thereof changes to +40 volts and the trouble alarm lamp LP230 is extinguished. The line circuit control switch 240 is retained in its trouble alarm test position until the high temperature condition in the temperature control station 20 is corrected so that the temperature-sensitive impedance device 250 will again exhibit a high impedance to current flow therethrough; at which time the line circuit control switch 240 is returned to its normal position and the circuit for operating the line circuit 220 is completed through the temperature-sensitive impedance device 250. The line circuit 220 is, at this time, then in its normal operating state, and is prepared to respond to another high temperature condition that may occur at the temperature control station 20, or to an open circuit condition that may develop in the line conductors 246A and 246B.

Section 5.—Operation of the high temperature alarm system when an open circuit condition develops in any of the line conductors

Assuming now that the circuit, extended via the line conductors 246A and 246B through the temperature-sensitive impedance device 250 at the temperature control station 20 for operating the line circuit 220 is interrupted by an open line condition in one of the conductors, such, for example, as the line conductor 246B, the normal 4 ma. current flow through the path including the line conductors, the resistors 231 and 232 and the collector-emitter path of the transistor TR221 is interrupted. Thereupon, the voltage at the emitter electrode of the transistor TR223 is changed from approximately -48 volts to ap-

proximately -60 volts on the terminal 203. At this time the transistor TR223 is biased conductive in the base-emitter path thereof so that approximately 3.3 ma. flows from the emitter thereof of which approximately 1.3 ma. is drawn from the collector electrode through the resistor 228, the additional 2 ma. being drawn through the base electrode of TR223. Thus, the 3.3 ma. flows from the emitter of TR223 through resistor 232, the collector-emitter path of TR221 and resistor 234 to -60 volts on the terminal 203, whereby the emitter electrode of TR223 is established at approximately -50 volts and the collector electrode is bottomed at approximately -50 volts. At this time then, the potential across the series connected resistor 229 and trouble lamp LP230 is increased from approximately 10 volts to 100 volts whereby the trouble lamp LP230 breaks down and sustains a 2 ma. current flow therethrough from the terminal 205, whereby the trouble lamp LP230 is illuminated to indicate an open line condition in the line 246. Thereupon, the collector current of TR223 is approximately 3 ma., with 1 ma. flowing through resistor 228, and the base current is reduced from 2 ma. to approximately .3 ma. Thus, the transistors TR221 and TR223 and the trouble lamp LP230 are conductive, and the transistor TR 222 is held nonconductive by a reverse bias of approximately 3.5 volts between the base and the emitter electrode thereof. The 2 ma. current flowing through the trouble lamp LP230 is drawn through the conductor 195 from the trouble alarm controller 130. In the trouble alarm controller 130, the 2 ma. current flowing in the conductor 195 is drawn in part through the current limiting resistor 133 and in part through the diode D135 so that the voltage on the base electrode of the transistor TR131 is established at approximately +47 volts, whereby the transistor TR131 is biased conductive in the emitter-base path thereof and supports a current flow therethrough and current flows via the emitter-collector path thereof and relay R136 from +50 volts at the junction between resistors 120 and 121 to +27.5 volts so that the collector electrode of TR131 is bottomed at approximately +50 volts. Due to the voltage drop through the base resistor 132 caused by the emitter-base path current the voltage on the terminal 205 is established at +48 volts which does not affect the operation of the trouble lamp LP230. The current flow through the emitter-collector path of TR131 energizes and operates the trouble relay R136, thereby closing at contacts 137 the previously traced circuit from +60 volts on the power conductor 194 via contacts 184 of the test switch 180 and the trouble alarm 190 to -60 volts on the power conductor 193. At this time the trouble arm 190 is operated thereby rendering an audible alarm to the attendant at the central station 10 that an open line condition exists on one of the control lines 246, etc., of the high temperature alarm system. The attendant then checks all of the trouble alarm lamps in the system and is given notice by the illuminated condition of trouble alarm lamp LP230 that the open line condition exists in the control line 246.

Reconsidering the initial operation of the transistor TR223 in the line circuit 220, the 2 ma. current flowing in the base-emitter path thereof is drawn through the conductor 197 from the voltage regulator 150. Therein, the 2 ma. current demand of conductor 197 tends to be supplied initially through the load resistor 159 from the power conductor 194, whereby the potential drop through the resistor 159 is increased and the voltage on the conductor 197 and the emitter electrodes of the transistors TR151 to TR154, inclusive, tends to change from -50 volts to approximately -51 volts. Thus, the voltage on the emitter electrodes tends to become negative with respect to the voltage on the base electrodes, thereby decreasing the current flow through the emitter-collector paths of the transistors TR151 to TR154, inclusive, by an aggregate of 2 ma. so that the current flow through the load resistor 159 remains substantially constant, and the voltage extended

to the terminal 207 by the conductor 197 remains at -50 volts. Thereafter, when the current flow through the base of the transistor TR223 in the line circuit 220 is reduced to .3 ma. the emitter electrodes of the transistors 5 TR151 to TR154 inclusive, in the voltage regulator 150 tends to swing positive with respect to the base electrodes thereof, whereby the total current flow through the transistor is increased by an amount of 1.7 ma. to compensate for the decrease in current drawn through the conductor 197.

Considering now the further operation of the line circuit 220, in response to the audible alarm rendered by the operation of the trouble alarm 190, the attendant at the central station 10 operates the line circuit control switch 15 240 associated with the control line 246 from its normal position through its cut-off and into its trouble-test position, whereby, as explained in Section 4 hereof, the line conductors 246A and 246B are disconnected from the line circuit 220 at contacts 242 and 244, and the load resistor 247 is connected to the line circuit 220 at contacts 241 and 243. A circuit is then completed from +60 volts at the terminal 204 via resistor 224, contacts 243, resistor 247, contacts 241, resistors 231 and 232, the collector-emitter path of the transistor TR221 and resistor 234 to 20 -60 volts on the terminal 203. The current through the above traced path is increased to 4 ma. so that the transistor TR223 is biased non-conductive at the emitter-electrode thereof by the -48 volts established at the junction between resistors 231 and 232. The collector potential 25 thereupon increases from -50 volts to approximately +40 volts, whereby the potential across trouble lamp LP230 is reduced to below the required conduction potential thereof and the trouble alarm lamp LP230 is rendered non-conductive. The current drawn through the conductor 195 of the trouble alarm controller 130 is reduced from 2 ma. to zero so that the transistor TR131 therein is rendered non-conductive and the relay R136 is restored. Thereupon, the previously traced circuit for 30 operating the trouble alarm 190 is interrupted at contacts 137. At this time, the line circuit 220 is disabled until the open line condition in control line 246 is repaired, and the common equipment at the central station 10 is restored to normal and again conditioned to respond to trouble alarm conditions and temperature alarm conditions that may occur in the other of the line circuits 220A, etc., of the high temperature alarm system. Thereafter, when the open line condition in the control line 246 is repaired the line circuit control switch 240 of the line circuit 220 is restored from its trouble-test position to its 35 normal position, thereby completing the previously traced circuit through the temperature-sensitive impedance device 250 at the temperature control station 20 and rendering the line circuit 220 normally operative to detect any high temperature condition that may arise at the temperature control station 20 and any further interruptions that may occur in the conductors of control line 246.

Section 6.—Operation of the high temperature alarm system when one of the line conductors therein is grounded

Now assuming that one of the conductors in one of the control lines extending between the line circuits 220, etc., and the corresponding temperature control stations 20, etc., is accidentally grounded, the one of the line conductor ground lamps LP116 and LP117 in the grounded line detector unit 110 corresponding to the polarity of the grounded conductor is illuminated, thereby rendering the attendant at the central station 10 an indication of the fault condition existing in the high temperature alarm system. Specifically, assuming that the line conductor 246A of the control line 246 extending from the line circuit 220 to the temperature control station 20 is accidentally grounded, the voltage on the conductor 246A is changed from -40 volts to zero volts, and the voltage on the line conductor 246B is changed from -40 volts to -80

volts. Thus, the potential on the negative power conductor 193 is established at -20 volts and the potential on the positive power conductor 194 is established at -100 volts. In the grounded line detector 110, the change in voltage on the power conductors 193 and 194 changes the voltages at the junctions between the resistors of the voltage divider therein so that the voltage at the junction between resistors 114 and 115 is raised from +50 volts to +90 volts, and the potential across the electrodes of the negative line conductor ground lamp LP117 is established at substantially 90 volts so that the lamp breaks-down and is illuminated.

In accordance with the illumination of the lamp LP117, the attendant at the central station 10 is given notice that the negative conductor of one of the control lines in the system is grounded, and thereafter attempts to locate the one control line in which the grounded negative conductor condition exists by individually operating each of the line circuit control switches 240, etc., one at a time, from its normal position through the cut-off and into the trouble-test position and then back to its normal position until the operated negative conductor lamp LP117 is extinguished. Specifically, when the line circuit control switch 240 is operated into its trouble-test position, the circuit extended via the conductors 246A and 246B is interrupted first at contacts 242 and 244, and immediately thereafter the load resistor 247 is connected at contacts 241 and 243 to the line circuit 220. At this time then, the grounded line conductor 246A is disconnected from the line circuit 220 and the line circuit 220 is normally operating so that the voltage on the power conductor 193 is changed from -20 volts to -60 volts, and the voltage on the power conductor 194 is changed from +100 volts to +60 volts. In accordance with the shift in the voltages on the power conductors 193 and 194, the voltages at the junction between resistors 113, 114 and 115 are shifted accordingly so that the potential across the electrodes of both line conductor ground lamps LP116 and LP117 is substantially below the required conduction potential thereof; hence, the illuminating current flow through the lamp LP117 is interrupted and the lamp is extinguished. At this time the line circuit 220 is disabled and the common equipment at the central station 10 is conditioned to respond to temperature alarm conditions or trouble alarm conditions that may occur in any other of the line circuits 220A, etc., or to a grounded conductor condition that may occur in any other of the control lines 248, etc.

The attendant at the central station 10 retains the line circuit control switch 240 in its trouble-test position until the grounded negative line conductor condition of the control line 246 is repaired, whereupon the line circuit control switch 240 is returned to its normal position and the circuit extended via the line conductors 246A and 246B through the temperature-sensitive impedance device 250 is again connected to the line circuit 220 so that the line circuit 220 is in its normal operating state with the transistor TR221 conducting. At this time, each of the line circuits 220, etc., are prepared to respond to a high temperature condition, an open line condition, and a grounded line conductor condition.

Now assuming that the line conductor 246B in the circuit extending from the line circuit 220 to the temperature control station 20 is accidentally grounded, the voltage on the conductor 246B is changed from +40 volts to zero volts and the voltage on the line conductor 246A is changed from -40 volts to -80 volts. Accordingly, the voltage on the negative power conductor 193 is changed to -100 volts, and the voltage on the positive power conductor 194 is changed to +20 volts and the voltages at the junctions between resistors 113, 114 and 115 in the grounded line detector 110 are shifted so that the potential across the electrodes of the positive line conductor ground lamp LP116 is approximately 90

volts and the lamp LP116 breaks down and supports an illuminating current flow therethrough. Thus, the attendant at the central station 10 is given notice of the fact that the positive line conductor of one of the control lines 246, etc., the high temperature alarm system is grounded.

In accordance with the illumination of the lamp LP116, the attendant at the central station 10 attempts to locate the one control line in which the grounded positive conductor condition exists by individually operating each of the line circuit switches 240, etc., one at a time, from its normal position through the cut-off and into the trouble-test position and then back to its normal position until the operated positive conductor lamp LP116 is extinguished. Specifically, when the line circuit control switch 240 is operated into its trouble-test position, the circuit extended via the conductors 246A and 246B is interrupted first at contacts 242 and 244, and immediately thereafter the load resistor 247 is connected at contacts 241 and 243 to the line circuit 220. At this time then, the grounded line conductor 246B is disconnected from the line circuit 220 and the line circuit 220 is normally operating, so that the voltage on the power conductor 193 is changed from -100 volts to -60 volts, and the voltage on the power conductor 194 is changed from +20 volts to +60 volts. In accordance with the shift in the voltages on the power conductors 193 and 194, the voltages at the junctions between resistors 113, 114 and 115 are shifted accordingly so that the potential across the electrodes of both line conductor ground lamps LP116 and LP117 is substantially below the conduction potential thereof; hence, the illuminating current flow through the lamp LP116 is interrupted, the lamp is extinguished, the line circuit 220 is disabled, and, as previously explained, the high temperature alarm system is conditioned to respond to alarm and fault conditions that may occur in the other of the line circuits and control conductors.

The attendant at the central station 10 retains the line circuit control switch 240 in its trouble-test position until the grounded positive line conductor condition of the control line 246 is repaired, whereupon the line circuit control switch 240 is returned to its normal position and the circuit extended via the line conductors 246A and 246B through the temperature-sensitive impedance device 250 is again connected to the line 220, so that the line circuit 220 is in its normal operating state with the transistor TR221 conducting. At this time, each of the line circuits 220, etc., are prepared to respond to a high temperature condition, an open line condition, and a grounded line conductor condition.

Section 7.—Testing the operation of the high temperature alarm system

The high temperature alarm system includes arrangements so that each of the line circuits may be tested for temperature alarm operation and trouble alarm operation easily and quickly from the attendant's position at the central station 10.

Assuming first that it is desired to test the operation of the line circuit 220 for a high temperature alarm condition, the test switch 180 is operated from its normal position into its temperature alarm test position, thereby closing contacts 181 and 182 and opening contacts 183 thereof. At contacts 181, the previously mentioned circuit for applying -60 volts from the power conductor 193 to the emitter electrodes of the transistors TR161 and TR162 of the flasher unit 160 is closed, whereby the flasher unit is operated.

Specifically, when contacts 181 are closed, one of the transistors, for example, TR161, is rendered conductive and the other TR162, is rendered non-conductive due to the lack of positive identity between the operating characteristics of the transistors. Thereupon, current flows in the circuit from +60 volts via resistor 167, the capacitor C171 and the base-emitter path of TR161 to -60 volts

and conduction in TR161 continues until the capacitor C171 charges and substantially blocks the current flow to the base thereof. With TR161 conducting the collector thereof is at substantially -60 volts and a large current flows from +60 volts via resistors 164 and 165 and the collector-emitter path of TR161 to -60 volts so that the junction between resistors 164 and 165 is at substantially 0 volts and current flows thereto from +60 volts via resistors 167 and 168, the collector-base path of TR162 and capacitor C172, thereby biasing the transistor TR162 non-conductive and establishing the collector voltage thereof at slightly less than +60 volts. Thereafter when the capacitor C171 is charged, the transistor TR161 is rendered non-conductive in the base-emitter path so that the collector current is cut off and the collector thereof and the junction between resistors 164 and 165 is established at approximately +60 volts. Thereupon current flows from +60 volts on the power conductor 194 via the resistor 164 and capacitor C172 through the base-emitter path of TR162 to -60 volts at the emitter thereof; whereby the latter transistor is rendered conductive and the collector voltage thereof is established at approximately -60 volts and the voltage at the junction between resistors 167 and 168 is established at approximately 0 volts so that a small reverse current is drawn through the collector-base path of transistor TR161 and capacitor C171 in order to discharge the latter capacitor. Thereafter, when the capacitor C172 is charged sufficiently to substantially cut off the current in the base-emitter path of TR162, the latter transistor is rendered non-conductive so that the collector voltage thereof is established at approximately +60 volts and the transistor TR161 is again rendered conductive. From the above description it is seen the voltage at the collector of TR162 changes abruptly from approximately +60 volts to approximately -60 volts and back to +60 volts to establish a substantially square wave voltage signal thereon. This voltage is employed to alternately illuminate and extinguish the test position lamp LP171 which has its anode electrode connected to approximately +50 volts at the junction between resistors 169 and 178 and its cathode electrode connected to the collector of TR162. When the potential on the collector of TR162 is at approximately +60 volts the lamp LP171 is extinguished and when the potential on the collector of TR162 is at approximately -60 volts the lamp LP171 conducts current and is illuminated. In this manner the test lamp LP171 is flashed at a rate of about five times a minute to indicate to the attendant at the central station 10 that the test switch 180 is in one of its test positions. As previously pointed out, the closing of contacts 182 and the opening of contacts 183 substitutes the series connected resistor 188 and the temperature alarm lamp LP189 for the temperature alarm 187 in the previously traced operating circuit therefor.

Thereafter, the attendant operates the line circuit control switch 240 from its normal position to its temperature alarm test position. In the temperature alarm test position a circuit is closed at contacts 245 for effectively short-circuiting the load resistor 252 of the temperature-sensitive impedance device 250 so that a low impedance condition is presented to the line circuit 220 and the line circuit 220 is operated as though a high temperature condition exists at the temperature control station 20, and in the manner as described in Section 4 hereof so that the transistor TR221 is substantially non-conducting and the transistor TR222 is conducting. Responsive to the operation of the transistor TR222, the temperature alarm lamp LP227 is illuminated and the temperature alarm controller 140 is operated so that relay R146 operates to close at contacts 147 the circuit for illuminating the temperature alarm test lamp LP189. In this manner the attendant at the central station 10 is rendered notice that the line circuit 220 operates properly in response to high temperature alarm conditions; thereupon the line circuit control switch 240 is operated from its temperature alarm test

position through its normal position to its cut-off position. As the switch 240 progresses from its normal position to its cut-off position the operating circuit through the line circuit 220 is interrupted at contacts 242 and 244 so that the transistor TR222 is rendered non-conductive, the alarm lamp LP227 is extinguished, the relay R146 in the temperature alarm controller 140 is restored, and the operating circuit through the temperature alarm test lamp LP189 is interrupted so that the lamp LP189 is extinguished; whereupon the line circuit control switch 240 is restored to its normal position thereby recompiling the circuit over the line conductors 246A and 246B from the line circuit 220 through the temperature-sensitive control device 250. At this time, the line circuit 220 is in its normal operating state and may be operated in response to either high temperature condition, an interrupted line conductor condition or a grounded line conductor condition to render an alarm at the central station 10. At the completion of the temperature alarm test, the test switch 180 is operated from its temperature alarm test position to its normal position, so that the flasher unit 160 is rendered inoperative and the temperature alarm 187 is substituted for the temperature alarm test lamp 189 in the operating circuit therefor. Thus, at this time, all of the equipment in the high temperature alarm system is rendered normally operative and responsive to high temperature conditions, interrupted line conductor conditions, and grounded line conductor conditions that may occur therein.

Now, assuming that it is desired to test the operation of the line circuit 220 for a trouble alarm condition, the test switch 180 is operated from its normal position into its trouble alarm test position, thereby closing contacts 185 and 186 and opening contacts 184 thereof. At contacts 186, the previously mentioned circuit for applying -60 volts from the power conductor 193 to the emitter electrodes of the transistors TR161 and TR162 of the flasher unit is operated in a manner as explained in this section to flash the test position lamp LP171 at the rate of five times a minute in order to indicate to the attendant at the central station 10 that the test switch 180 is in one of its test positions. As previously pointed out, the closing of contacts 185 and the opening of contacts 184 substitutes the series connected resistor 191 and the trouble alarm test lamp LP192 of the trouble alarm 190 in the previously traced operating circuit therefor.

Thereafter the attendant operates the line circuit test switch 240 from its normal position through its cut-off position and into its trouble-test position, whereby the circuit extended via line conductors 246A and 246B to the temperature control station 20 is interrupted at contacts 242 and 244, presenting for a brief interval an interrupted line conductor condition to the line circuit 220, and whereby thereafter the load resistor 247 is connected to the line circuit 220 at contacts 241 and 243 in order to render the line circuit normally operating. During the brief interval that the interrupted line conductor condition is presented to the line circuit 220, the transistor TR223 is operated in the manner as described in Section 5 hereof so that the trouble alarm lamp LP230 is flashed and the relay R136 in the trouble alarm controller 130 is operated and restored to close and interrupt at contacts 137 the previously prepared circuit through the trouble alarm test lamp LP192 so that the lamp LP192 is flashed. Thus, when the trouble alarm lamp LP230 and the trouble alarm test lamp LP192 are flashed to the attendant at the central station 10 is rendered notice that the line circuit 220 operates properly in response to an interrupted line conductor condition. Thereupon, the line circuit control switch 240 is operated from the trouble-test position through the cut-off position and into the normal position causing the trouble alarm lamp LP230 and the trouble alarm test lamp LP192 to again flash, and finally connecting the line conductors 246A and 246B to the line

circuit 220, whereby the line circuit 220 is rendered normally operating and is prepared to respond, in the manner as previously explained, to a high temperature condition, an interrupted line conductor condition and a grounded line conductor condition. Further, the test switch 180 is operated from its trouble alarm test position to its normal position thereby interrupting at contacts 186 the circuit for operating the flasher 160 and opening contacts 185 and closing contacts 184 to replace the trouble alarm test lamp LP192 with the trouble alarm 190 in the previously traced circuit therefor. At this time the high temperature alarm system is in its normal operating state and is prepared to respond to a high temperature condition that may occur at any of the temperature control stations 20, etc., thereof and is prepared to respond to an interrupted line conductor condition and a grounded line conductor condition that may occur in any of the control lines 246, etc.

The alarm system of the invention has been described in terms of a high temperature alarm system, and while at present this is considered to be the preferred embodiment of the invention it is understood that the alarm system might easily be adapted to a low temperature alarm system, and is not limited to rendering temperature alarms but may be adapted to respond to any one of a number of other physical phenomenon including, for example, light, pressure, and humidity. In any event, it is clear that various modifications may be made in the described embodiment, and it is intended to cover in the appended claims all such modifications that fall within the true spirit and scope of the invention.

What is claimed is:

1. An alarm system comprising a plurality of control stations; a central station; a plurality of two-conductor lines respectively extending from said control stations to said central station; each of said control stations being provided with a device selectively responsive to normal and abnormal conditions thereat respectively to establish corresponding normal and abnormal impedance connections between the conductors of the line extending thereto; a source of power provided with a reference voltage terminal and a low voltage terminal and a high voltage terminal; a plurality of line circuits at said central station and respectively associated with said lines; each of said line circuits including a first connection from said high voltage terminal to one of the conductors of the associated line, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a first transistor provided with a base connected to the junction between said second biasing resistor and said third biasing resistor and a collector connected via said first control resistor to the other of the conductors of the associated line and an emitter connected via said second control resistor to said reference voltage terminal, and a second transistor provided with a base connected to the junction between said first control resistor and the collector of said first transistor and a collector connected to the junction between said first biasing resistor and said second biasing resistor and an emitter connected to said low voltage terminal, whereby in any one of said line circuits the first transistor is rendered conductive in response to a normal impedance connection at the corresponding control station and the second transistor is rendered conductive in response to an abnormal impedance connection at the corresponding control station and wherein the first transistor is rendered substantially non-conductive in response to conduction of the second transistor so that the second transistor is maintained conductive irrespective of subsequent change of the impedance connection at the corresponding control station; an alarm indicator at

said central station; and means responsive to conduction of the second transistor in any one of said line circuits for selectively operating said alarm indicator to signify the abnormal condition at the corresponding one of said control stations.

2. An alarm system comprising a plurality of control stations; a central station; a plurality of two-conductor lines respectively extending from said control stations to said central station; each of said control stations being provided with a device selectively responsive to normal and abnormal conditions thereat respectively to establish corresponding normal and abnormal impedance connections between the conductors of the line extending thereto; a source of power provided with a reference voltage terminal and a low voltage terminal and a high voltage terminal; a plurality of line circuits at said central station and respectively associated with said lines; each of said line circuits including a first connection from said high voltage terminal to one of the conductors of the associated line, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a third control resistor, a first transistor provided with a base connected to the junction between said second biasing resistor and said third biasing resistor and a collector connected via said first control resistor and said second control resistor to the other of the conductors of the associated line and an emitter connected via said third control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a fourth biasing resistor, and a third transistor provided with a base connected to said low voltage terminal and a collector connected via said fourth biasing resistor to said high voltage terminal and an emitter connected to the junction between said first control resistor and said second control resistor, whereby in any one of said line circuits the first transistor normally is conductive in response to a normal impedance connection extended thereto from the corresponding control station and the second transistor is conductive in response to an abnormal impedance connection extended thereto from the corresponding control station and the first and third transistors are conductive in response to an interruption in the impedance connection normally extended thereto from the corresponding control station and wherein the first transistor is substantially non-conductive in response to conduction of the second transistor so that the second transistor is maintained conductive irrespective of subsequent change at the corresponding control station of the abnormal impedance connection to the normal impedance connection; a first alarm indicator at said central station; means responsive to the conduction of the second transistor in any one of said line circuits for selectively operating said first alarm indicator to signify the abnormal condition at the corresponding one of said control stations; a second alarm indicator at said central station; and means responsive to the conduction of the third transistor in any one of said line circuits for selectively operating said second alarm indicator to signify an interruption in the connection between said one line circuit and the corresponding control station.
3. An alarm system comprising a plurality of control stations; a central station; a plurality of two-conductor lines respectively extending from said control stations to said central station; each of said control stations being provided with a device selectively responsive to normal and abnormal conditions thereat respectively to establish corresponding normal and abnormal impedance connec-

tions between the conductors of the line extending thereto; a source of power provided with a reference voltage terminal and a low voltage terminal and a high voltage terminal; a plurality of line circuits at said central station and respectively associated with said lines; each of said line circuits including a first connection from said high voltage terminal to one of the conductors of the associated line, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a first transistor provided with a base connected to the junction between said second biasing resistor and said third biasing resistor and a collector connected via said first control resistor to the other of the conductors of the associated line and an emitter connected via said second control resistor to said reference voltage terminal, a second transistor provided with a base connected to the junction between said first control resistor and the collector of said first transistor and a collector of said first transistor and a collector connected to the junction between said first biasing resistor and said second biasing resistor and an emitter connected to said low voltage terminal, and an output terminal connected to the junction between said first and second biasing resistors and the collector of said second transistor, whereby in any one of said line circuits the first transistor normally is conductive in response to a normal impedance connection at the corresponding control station and the second transistor is conductive in response to an abnormal impedance connection at the corresponding control station and wherein the output terminal has a marking voltage applied thereto in response to conduction of the second transistor and wherein the first transistor is substantially non-conductive in response to conduction of the second transistor so that the second transistor is maintained conductive irrespective of subsequent change of the impedance connection at the corresponding control station; and indicator means at said central station comprising a load resistor and a plurality of diodes of the gas discharge type respectively associated with said line circuits and each provided with a cathode connected to the output terminal of the corresponding line circuit and an anode connected via said load resistor to said high voltage terminal, whereby any one of said diodes is discharged and illuminated in response to said marking voltage on the output terminal of the corresponding line circuit; an alarm device at said central station; and means responsive to the illumination of any one of said diodes for operating said alarm device to signify the abnormal condition at the one of the control stations corresponding to the illuminated diode.

4. An alarm system comprising a plurality of control stations; a central station; a plurality of two-conductor lines respectively extending from said control stations to said central station; each of said control stations being provided with a device selectively responsive to normal and abnormal conditions therat respectively to establish corresponding normal and abnormal impedance connections between the conductors of the line extending thereto; a source of power provided with a reference voltage terminal and a low voltage terminal and a high voltage terminal; a plurality of line circuits at said central station and respectively associated with said lines; each of said line circuits including a first connection from said high voltage terminal to one of the conductors of the associated line, a first biasing resistor, a second biasing resistor, a third biasing resistor, a second connection from said high voltage terminal via said first biasing resistor and second biasing resistor and said third biasing resistor to said reference voltage terminal, a first control resistor, a second control resistor, a third control resistor, a first transistor provided with a base connected to the junction between said second biasing resistor and said third bias-

ing resistor and a collector connected via said first control resistor and said second control resistor to the other of the conductors of the associated line and an emitter connected via said third control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a fourth biasing resistor, a third transistor provided with a base connected to said low voltage terminal and a collector connected via said fourth biasing resistor to said high voltage terminal and an emitter connected to the junction between said first control resistor and said second control resistor, a first output terminal connected to the junction between said first and second biasing resistors and the collector of said second transistor, and a second output terminal connected to the junction between said fourth biasing resistor and the collector of said third transistor, whereby in any one of said line circuits the first transistor normally is conductive in response to a normal impedance connection extended thereto from the corresponding control station and the second transistor is conductive in response to an abnormal impedance connection extended thereto from the corresponding control station and the first and third transistors are conductive in response to an interruption in the impedance connection normally extended thereto from the corresponding control station and wherein the first transistor is substantially non-conductive in response to conduction of the second transistor so that the second transistor is maintained conductive irrespective of subsequent change at the corresponding control station of the abnormal impedance connection to the normal impedance connection and wherein the first output terminal has a marking voltage applied thereto in response to conduction of the second transistor and wherein the second output terminal has the marking voltage applied thereto in response to conduction of the third transistor; first indicator means at said central station comprising a first load resistor and a plurality of first diodes of the gas discharge type respectively associated with said line circuits and each provided with a cathode connected to the first output terminal of the corresponding line circuit and an anode connected via said first load resistor to said high voltage terminal, whereby any one of said first diodes is discharged and illuminated in response to said marking voltage on the first output terminal of the corresponding line circuit; a first alarm in said central station; and means responsive to the illumination of any one of said first diodes for operating said first alarm to signify the abnormal condition at the one of the control stations corresponding to the illuminated first diode; second indicator means at said central station comprising a second load resistor and a plurality of second diodes of the gas discharge type respectively associated with said line circuits and each provided with a cathode connected to the second output terminal of the corresponding line circuit and an anode connected via said second load resistor to said high voltage terminal, whereby any one of said second diodes is discharged and illuminated in response to said marking voltage on the second output terminal of the corresponding line circuit; a second alarm at said central station; and means responsive to the illumination of any one of said second diodes for operating said second alarm to signify the interruption of the impedance connection normally extended from the one of the control stations to the illuminated second diode.

5. An alarm system comprising a plurality of control stations; a central station; a plurality of two-conductor lines respectively extending from said control stations to said central station; each of said control stations being provided with a device selectively responsive to normal and abnormal conditions thereat respectively to establish

corresponding normal and abnormal impedance connections between the conductors of the line extending thereto; a source of power provided with a reference voltage terminal and a low voltage terminal and an high voltage terminal; a plurality of line circuits at said central station and respectively associated with said lines; each of said line circuits including a pair of input terminals, a first connection from said high voltage terminal to one of said input terminals, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a third control resistor, a first transistor provided with a base connected to the junction between said second biasing resistor and said third biasing resistor and a collector connected via said first control resistor and said second control resistor to the other of said input terminals and an emitter connected via said third control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a fourth biasing resistor, a third transistor provided with a base connected to said low voltage terminal and a collector connected via said fourth biasing resistor to said high voltage terminal and an emitter connected to the junction between said first control resistor and said second control resistor, a first output terminal connected to the junction between said first and second biasing resistors and the collector of said second transistor, and a second output terminal connected to the junction between said fourth biasing resistor and the collector of said third transistor; a plurality of line circuit control means respectively disposed between the line circuits and the corresponding lines; each of said line circuit control means including an impedance device having an impedance value corresponding to that of the normal impedance connection in the corresponding control station and a control switch selectively operable into a first position and a second position and a third position, the control switch of any one of said line circuit control means being normally in the first position and completing thereat connections from the conductors of the corresponding line respectively to the input terminals of the corresponding line circuit, whereby in any one of said line circuits the first transistor normally is conductive in response to a normal impedance connection extended thereto from the corresponding control station and the second transistor is conductive in response to an abnormal impedance connection extended thereto from the corresponding control station and the first and third transistors are conductive in response to an interruption in the impedance connection normally extended thereto from the corresponding control station and wherein the first transistor is substantially non-conductive in response to conduction of the second transistor so that the second transistor is maintained conductive irrespective of subsequent change at the corresponding control station of the abnormal impedance connection to the normal impedance connection and wherein the first output terminal has a marking voltage applied thereto in response to conduction of the second transistor and wherein the second output terminal has the marking voltage applied thereto in response to conduction of the third transistor, the control switch of any one of said line circuit control means in the second position interrupting thereat the connections between the corresponding line circuit and the conductors of the corresponding line in order to effect interrupted impedance connection operation of the line circuit so that the first and third transistors thereof are conductive, the control switch of any one of said line circuit control means in the third

position completing thereat connections between the impedance device thereof and the corresponding line circuit in order to effect normal impedance connection operation of the line circuit to that the first transistor thereof is conductive; first indicator means at said central station comprising a first load resistor and a plurality of first diodes of the gas discharge type respectively associated with said line circuits and each provided with a cathode connected to the first output terminal of the corresponding line circuit and an anode connected via said first load resistor to said high voltage terminal, whereby any one of said first diodes is discharged and illuminated in response to said marking voltage on the first output terminal of the corresponding line circuit; a first alarm at said central station; means responsive to the illumination of any one of said first diodes for operating said first alarm to normally signify the abnormal condition at the one of the control stations corresponding to said illuminated first diode; second indicator means at said central station comprising a second load resistor and a plurality of second diodes of the gas discharge type respectively associated with said line circuits and each provided with a cathode connected to the second output terminal of the corresponding line circuit and an anode connected via said second load resistor to said high voltage terminal, whereby any one of said second diodes is discharged and illuminated in response to said marking voltage on the second output terminal of the corresponding line circuit; a second alarm at said central station; and means responsive to the illumination of any one of said second diodes for operating said second alarm to signify the interruption of the impedance connection normally extended from the one of the control stations corresponding to said illuminated second diode; whereby upon occurrence of an abnormal condition at any one of said control stations and pending the reinstatement of the normal condition thereat the operated first alarm is restored and the illuminated one of said first diodes is extinguished by operating the control switch of the corresponding line circuit control means from the first position through the second position and into the third position in order to operate the corresponding line circuit so that the second transistor is rendered non-conductive and the first transistor is rendered conductive; and whereby upon interruption of any one of the impedance connections normally extended between the control stations and the line circuits and pending the repair of the interruption therein the operated second alarm is restored and the illuminated one of said second diodes is extinguished by operating the control switch of the corresponding line circuit control means from the first position into the third position in order to operate the corresponding line circuit so that the third transistor is rendered non-conductive.

5 6. An alarm system comprising a plurality of control stations; a central station; a plurality of two-conductor lines respectively extending from said control stations to said central stations; each of said control stations being provided with a device selectively responsive to normal and abnormal conditions thereat respectively to establish corresponding normal and abnormal impedance connections between the conductors of the line extending thereto; a source of power provided with a reference voltage terminal and a low voltage terminal and a high voltage terminal; a plurality of line circuits at said central station and respectively associated with said lines; each of said line circuits including a pair of input terminals, a first connection from said high voltage terminal to one of said input terminals, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a third control resistor, a first transistor provided with a base connected to the junction between said second biasing resistor and said third biasing resistor and a collector connected via said first control resistor and said second control resistor to the other of said input terminals and an emitter connected via said third control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a fourth biasing resistor, a third transistor provided with a base connected to said low voltage terminal and a collector connected via said fourth biasing resistor to said high voltage terminal and an emitter connected to the junction between said first control resistor and said second control resistor, a first output terminal connected to the junction between said first and second biasing resistors and the collector of said second transistor, and a second output terminal connected to the junction between said fourth biasing resistor and the collector of said third transistor; a plurality of line circuit control means respectively disposed between the line circuits and the corresponding lines; each of said line circuit control means including an impedance device having an impedance value corresponding to that of the normal impedance connection in the corresponding control station and a control switch selectively operable into a first position and a second position and a third position, the control switch of any one of said line circuit control means being normally in the first position and completing thereat connections from the conductors of the corresponding line respectively to the input terminals of the corresponding line circuit, whereby in any one of said line circuits the first transistor normally is conductive in response to a normal impedance connection extended thereto from the corresponding control station and the second transistor is conductive in response to an abnormal impedance connection extended thereto from the corresponding control station and the first and third transistors are conductive in response to an interruption in the impedance connection normally extended thereto from the corresponding control station and wherein the first transistor is substantially non-conductive in response to conduction of the second transistor so that the second transistor is maintained conductive irrespective of subsequent change at the corresponding control station of the abnormal impedance connection to the normal impedance connection and wherein the first output terminal has a marking voltage applied thereto in response to conduction of the second transistor and wherein the second output terminal has the marking voltage applied thereto in response to conduction of the third transistor, the control switch of any one of said line circuit control means in the second position interrupting thereat the connections between the corresponding line circuit and the conductors of the corresponding line in order to effect interrupted impedance connection operation of the line circuit so that the first and third transistors thereof are conductive, the control switch of any one of said line circuit control means in the third

between said second biasing resistor and said third biasing resistor and a collector connected via said first control resistor and said second control resistor to the other of said input terminals and an emitter connected via said third control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a fourth biasing resistor, a third transistor provided with a base connected to said low voltage terminal and a collector connected via said fourth biasing resistor to said high voltage terminal and an emitter connected to the junction between said first control resistor and said second control resistor, a first output terminal connected to the junction between said first and second biasing resistors and the collector of said second transistor, and a second output terminal connected to the junction between said fourth biasing resistor and the collector of said third transistor; a plurality of line circuit control means respectively disposed between the line circuits and the corresponding lines; each of said line circuit control means including an impedance device having an impedance value corresponding to that of the abnormal impedance connection in the corresponding control station and a test switch selectively operable into a first position and a second position and a third position, the test switch of any one of said line circuit control means being normally in the first position and completing thereat connections from the conductors of the corresponding line respectively to the input terminals of the corresponding line circuit, whereby in any one of said line circuits the first transistor normally is conductive in response to a normal impedance connection extended thereto from the corresponding control station and the second transistor is conductive in response to an abnormal impedance connection extended thereto from the corresponding control station and the first and third transistors are conductive in response to an interruption in the impedance connection normally extended thereto from the corresponding control station and wherein the first transistor is substantially non-conductive in response to conduction of the second transistor so that the second transistor is maintained conductive irrespective of subsequent change at the corresponding control station of the abnormal impedance connection to the normal impedance connection and wherein the first output terminal has a marking voltage applied thereto in response to conduction of the second transistor and wherein the second output terminal has the marking voltage applied thereto in response to conduction of the third transistor, the test switch of any one of said line circuit control means in the second position interrupting thereat the connections between the corresponding line circuit and the conductors of the corresponding line in order to effect interrupted impedance connection operation of the corresponding line circuit so that the first and third transistors thereof are conductive, the test switch of any one of said line circuit control means in the third position completing thereat connections between the impedance device thereof and the corresponding line circuit in order to effect abnormal impedance connection operation of the corresponding line circuit so that the second transistor thereof is conductive; first indicator means at said central station comprising a first load resistor and a plurality of first diodes of the gas discharge type respectively associated with said line circuits and each provided with a cathode connected to the first output terminal of the corresponding line circuit and an anode connected via said first load resistor to said high voltage terminal, whereby any one of said first diodes is discharged and illuminated in response to said marking voltage on the first output terminal of the corresponding line circuit; a first alarm at said central station; means responsive to the illumination of any one of said first diodes for operating said first alarm

to normally signify the abnormal condition at the one of the control stations corresponding to said illuminated first diode; second indicator means at said central station comprising a second load resistor and a plurality of second diodes of the gas discharge type respectively associated with said line circuits and each provided with a cathode connected to the second output terminal of the corresponding line circuit and an anode connected via said second load resistor to said high voltage terminal, whereby by any one of said second diodes is discharged and illuminated in response to said marking voltage on the second output terminal of the corresponding line circuit; a second alarm at said central station; and means responsive to the illumination of any one of said second diodes for operating said second alarm to signify the interruption of the impedance connection normally extended from the one of the control stations corresponding to said illuminated second diode; whereby any one of said line circuits may be tested for interrupted impedance connection operation by operating the test switch of the corresponding line circuit control means from the first position through the second position to the first position in order to render conductive and non-conductive the third transistor thereof and thereby to operate and restore the corresponding second diode and the second alarm; and whereby any one of said line circuits may be tested for abnormal impedance connection operation by operating the test switch of the corresponding line circuit control means from the first position through the third position and the second position to the first position in order to render conductive and non-conductive the second transistor thereof and thereby to operate and restore the corresponding first diode and the first alarm.

7. In an alarm system including a control station, a central station, a two-conductive line extending from the control station to the central station, the control station being provided with a device selectively responsive to normal and abnormal conditions thereat respectively to establish corresponding normal and abnormal impedance connections between the conductors of the line extending thereto, and a line circuit at said central station associated with said two-conductor line; the line circuit combination comprising a source of power provided with a reference voltage terminal and a low voltage terminal and a high voltage terminal, a first connection from said high voltage terminal to one of the conductors of the associated line, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a first transistor provided with a base connected to the junction between said second biasing resistor and said third biasing resistor and a collector connected via said first control resistor to the other of the conductors of the associated line and an emitter connected via said second control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a third control resistor, an alarm indicator, and a third connection from the junction between said first and second biasing resistors and the collector of said second transistor via said third control resistor and said alarm indicator to said high voltage terminal, whereby in any one of said line circuits the first transistor is rendered conductive in response to a normal impedance connection at the corresponding control station and the second transistor is rendered conductive in response to an abnormal impedance connection at the corresponding control station and wherein the first transistor is rendered substantially non-conductive in response to conduction of the second transistor

so that the second transistor is maintained conductive irrespective of subsequent change of the impedance connection at the corresponding control station and wherein the alarm indicator is operated in response to conduction of the second transistor to signify the abnormal condition at the corresponding control station.

8. The alarm system including the line circuit combination set forth in claim 7, wherein said alarm indicator is of the gas diode discharge type.

9. In an alarm system including a control station, a central station, and a two-conductor line extending from the control station to the central station, the control station being provided with a device selectively responsive to normal and abnormal conditions thereat respectively to establish corresponding normal and abnormal impedance connections between the conductors of the line extending thereto, and a line circuit at the central station associated with the two-conductor line; the line circuit combination comprising a source of power provided with a reference voltage terminal and a low voltage terminal and a high voltage terminal, a first connection from said high voltage terminal to a first of the conductors of the associated line, a first biasing resistor, a second biasing resistor, a third biasing resistor, a second connection from said high voltage terminal via said first biasing resistor and said second biasing resistor and said third biasing resistor to said reference voltage terminal, a first control resistor, a second control resistor, a third control resistor, a first transistor provided with a base connected to the junction between said second biasing resistor and said third biasing resistor and a collector connected via said first control resistor and said second control resistor to the other of the conductors of the associated line and an emitter connected via said third control resistor to said reference voltage terminal, a second transistor provided with a base connected to the junction between said first control resistor and the collector of said first transistor and a collector connected to the junction between said first biasing resistor and said second biasing resistor and an emitter connected to said low voltage terminal, a fourth biasing resistor, a third transistor provided with a base connected to said low voltage terminal and a collector connected via said fourth biasing resistor to said high voltage terminal and an emitter connected to the junction between said first control resistor and said second control resistor, a fourth control resistor, a first alarm indicator, a third connection from the junction between said first and second biasing resistors and the collector of said second transistor via said fourth control resistor and said first alarm indicator to said high voltage terminal, a fifth control resistor, a second alarm indicator and a fourth connection from the junction between said fourth biasing resistor and the collector of said third transistor via said fifth control resistor and said second alarm indicator to said high voltage terminal whereby in any one of said line circuits the first transistor normally is conductive in response to a normal impedance connection extended thereto from the corresponding control station and the second transistor is conductive in response to an abnormal impedance connection extended thereto from the corresponding control station and the first and third transistors are conductive in response to an interruption in the impedance connection normally extended thereto from the corresponding control station and wherein the first transistor is substantially non-conductive in response to conduction of the second transistor so that the second transistor is maintained conductive irrespective of subsequent change of the abnormal impedance connection to the normal impedance connection at the corresponding control station and the first alarm indicator is operated in response to conduction of the second transistor and the second alarm indicator is operated in response to conduction of the third transistor, so that an abnormal condition in any one of said control stations is signified by the operation of the corresponding first

alarm indicator and the interruption in the impedance connection normally extended between any one of said control stations and the corresponding line circuit is signified by the operation of the corresponding second alarm indicator.

10. An alarm system comprising a plurality of control stations, a central station, a plurality of lines respectively extending from said control stations to said central station, each of said control stations being provided with a device selectively responsive to a normal condition and to an abnormal condition thereat respectively to apply corresponding normal and abnormal signals to the individual line extending thereto, a plurality of line circuits at said central station and respectively associated with said lines, each of said line circuits including a transistor network selectively operative into a normal condition and into a first abnormal condition in response to the application of said respective normal and abnormal signals to the individually associated line and operative into a second abnormal condition in response to the interruption of said individually associated line, an alarm indicator at said central station, means responsive to said first abnormal operating condition of the transistor network in any one of said line circuits for selectively operating said alarm indicator to signify the abnormal condition at the corresponding one of said control stations, and means responsive to said second abnormal operating condition of the transistor network in any one of said line circuits for selectively operating said alarm indicator to 30 signify the interruption of the corresponding one of said individual lines.

11. An alarm system comprising a plurality of control stations, a central station, a plurality of lines respectively extending from said control stations to said central station, each of said control station being provided with a device selectively responsive to a normal condition and to an abnormal condition thereat respectively to apply corresponding normal and abnormal signals to the individual line extending thereto, a plurality of line circuits at said central station and respectively associated with said lines, each of said line circuits including a biasing network selectively operative into a normal condition and into a first abnormal condition in response to the application of said respective normal and abnormal signals to the individually associated line and operative into a second abnormal condition in response to the interruption of said individually associated line, each of said line circuits further including a transistor network selectively operative into a normal condition and into a first abnormal condition and into a second abnormal condition in response to the operation of said biasing network thereof into said respective normal and first abnormal and second abnormal conditions, an alarm indicator at said central station, means responsive to said first abnormal operating condition of the transistor network in any one of said line circuits for selectively operating said alarm indicator to signify the abnormal condition at the corresponding one of said control stations, and means responsive to said second abnormal operating condition of the transistor network in any one of said line circuits for selectively operating said alarm indicator to 50 signify the interruption of the corresponding one of said individual lines.

12. An alarm system comprising a plurality of alarm stations, a central station, a plurality of lines respectively extending from said alarm stations to said central station, each of said lines being arranged in a closed circuit individual thereto, each of said alarm stations being provided with a device selectively responsive to a normal condition and to an abnormal condition thereat respectively to establish corresponding normal and abnormal impedance conditions in the individual line extending thereto, opening of the circuit in any one of said lines establishing an alarm impedance condition therein, a plurality of line circuits at said central station and respectively associated with said lines, each of said line circuits including a trans-

sistor network selectively operative into normal and abnormal and alarm conditions in response to the corresponding normal and abnormal and alarm impedance conditions in the individually associated line, an alarm indicator at said central station, means responsive to the abnormal operating condition of the transistor network in any one of said line circuits for selectively operating said alarm indicator to signify the abnormal condition at the corresponding one of said alarm stations, and means responsive to the alarm operating condition of the transistor network in any one of said line circuits for selectively operating said alarm indicator to signify the opening of the circuit in the corresponding one of said lines.

5

10

13. The alarm system set forth in claim 12, and further comprising means responsive to operation of said alarm indicator to signify an abnormal condition at any one of said alarm stations for locking said alarm indicator in its operated position independently of the subsequent normal or abnormal condition at the signified alarm station, and reset means for unlocking said alarm indicator.
